FIG. 1 is a top, front, right-side perspective view of a shower head holder showing new design in its intended environment.

FIG. 2 is a top, front, right-side perspective view thereof;

FIG. 3 is a front-side elevational view thereof;

FIG. 4 is a left-side elevational view thereof;

FIG. 5 is a top plan view thereof;

FIG. 6 is a back-side elevational view thereof;

FIG. 7 is a left-side elevational view thereof; and,

FIG. 8 is a bottom plan view thereof.

The broken line showing of a shower head is for illustrative purposes only and forms no part of the claimed design.
